DISMOUNTABLE CASE

Hans Erik Edvin Holst, Lidingo, Sweden, assignor to Hyresgästernas Sparkasse- och Byggnadeförenings Riksförbund u. p. a., Stockholm, Sweden, a corporation of Sweden

Application December 20, 1949, Serial No. 133,983
In Sweden May 6, 1949

4 Claims. (Cl. 217—12)

1

This invention relates to dismountable cases and more particularly to cases of this kind having a removable bottom and at least four removable side walls and, as the case may be, a removable cover.

Several constructions of such cases are previously known, but as a rule they suffer from the disadvantage that the assembly of the case is troublesome.

My invention has for its principal object to provide for a considerable simplification and improvement in the assembly of the case by locating the side walls and the bottom of the case firmly in correct interrelation even before mounting the cover and strapping the case. In the previously known constructions special arrangements have generally to be resorted to in order, during packing and unpacking to hold the side walls in place before mounting the cover since otherwise the side walls might fall inward or outward.

Another object of the invention is to provide a dismountable case which is light of weight and does not involve the use of costly or weighty fittings.

According to the invention, for the objects stated, in a case of the kind described each of two oppositely disposed side walls is provided at two lateral edges with ribs or laths disposed perpendicularly to the bottom and arranged on the outwardly facing surface of said side walls, said ribs or laths being adapted to engage corresponding channels or grooves in edge bars at the adjacent side walls so as to locate the side walls in fixed interrelation. The first-mentioned side walls, for instance the end walls, are provided with transverse tongues, plates, projections, shoulders or the like abutments which, in the mounted condition of the case, engage and overlap the above-mentioned channelled edge bars and, by affording support for the latter, prevent said end walls from falling inward.

Preferably the bottom rests on edge ribs attached to the lower inner edges of two opposite side walls, the two remaining opposite side walls being provided with bars or lists which project downward beyond the upper surface of the bottom and preferably terminate at the level of the under-side of the bottom in order to locate the bottom and said side walls in fixed interrelation.

Said tongues may consist of short sheet-metal plates which are secured onto said bars or lists or other elements of the said side walls by securing elements such as screws. By this means the corresponding side walls will be located

2

against both inwardly and outwardly directed displacements.

The invention will now be described more in detail in connection with the accompanying drawing illustrating, by way of example, a preferred embodiment thereof, and in which:

Figure 1 is a vertical elevation in longitudinal section showing a case according to the invention in mounted condition.

Figure 2 illustrates an end elevation of the case.

Figure 3 shows a top view of the same, part of the cover being broken away.

Figure 4 shows a vertical cross-section of the case.

Figure 5 illustrates, to a larger scale, a fractional perspective view of one corner of the case, some of the external parts being cut away to show the inner parts.

Figure 6 illustrates, to a larger scale, an external perspective view of the same corner.

Referring to the drawings, in the embodiment illustrated, the case consists of two longside walls 1, 1a, two end walls 2, 2a, a bottom 3 and a cover 3a. The longside walls 1, 1a are provided at their vertical edge portions with edge ribs or bars 4 (Figs. 3, 5 and 6) nailed, screwed or glued thereto and having each a longitudinal channel or groove 5, whereby said ribs or bars 4 obtain an L-shaped cross-section, as will be seen from Figs. 5 and 6. The end walls 2, 2a are provided at their vertical edges with laths 6 which engage said channels 5, as will be apparent from Fig. 6, so that the end walls 2, 2a interconnect the two opposite longside walls 1 and 1a, respectively, and are at the same time preventing themselves from falling outward.

In order to prevent the end walls from falling inward they are provided with transverse tongues 7 of, for instance, flat iron bar pieces attached

by screws or otherwise to vertical bars 8 which may serve simultaneously for interconnecting the boards of the end walls 2, 2a. The said tongues 7 slightly overlap the outer surface of the edge bars 4 so as to locate the end walls 2,

2a so that they are prevented from falling inward. The bars 8 preferably extend downward as far as to the underside of the bottom 3, whereby they prevent the bottom from longitudinal displacement. The bottom 3 is supported on edge

bars 9 which are disposed on the lower edge portions of the side walls 1, 1a, whereby the bottom is prevented from being dropped. The boards of the bottom are interconnected by means of longitudinal bars 11 parallel to bars 9.

Similarly, the bars 8 may be extended as far

as the level of the upper surface of the cover 3a in order to secure the cover against longitudinal movement. The cover is laterally located by the side walls 1, 1a.

In mounting the case the walls 1, 1a are first placed in vertical position spaced apart at a distance corresponding to the width of the bottom 3 and with their bars 9 facing each other at the lower edges of said walls 1, 1a. Now the bottom 3 is placed horizontally onto the edge bars 9, and then the end walls 2, 2a with their laths 6 are slid down into the channels 5 of the walls 1, 1a and with the tongues 7 engaging the bars 4. The case now forms a rigid unitary structure in spite of the cover having not yet been put in place. After having packed the case, the cover 3a is put on and then the case may be strapped in any suitable well-known manner. Ribs 10 may be attached to the cover 3a, the walls 1, 1a and the bottom in order to stabilize the strapping (which may be effected by means of iron straps).

It will be understood that the invention may be modified in various ways without departing from its scope. Thus, for instance, the tongues 7 could be replaced by wooden projections which might be integral with the ribs or bars 8, if desired.

What I claim is:

1. In a dismountable case the combination of a removable cover and bottom and four individually removable side walls which are vertical when the case rests on its bottom, and which are arranged in pairs oppositely and in parallel relationship to each other, ribs being provided at two opposite vertical edges at the outer surface of each of two of the oppositely disposed side walls of said case, said ribs being disposed perpendicularly to said bottom, vertical edge bars at the adjacent edges of the other two opposite side walls, a longitudinal channel in each of said edge bars and opening toward the said ribs at the adjacent side walls, said ribs engaging said channels to prevent the first-mentioned rib-carrying side walls from falling outward, and abutments provided on said first-mentioned rib-carrying side walls and overlapping and supporting said channelled edge bars to prevent said first-mentioned side walls from falling inward, said case further comprising edge bars attached to the inner surface of the lower edge portions of two opposite side walls to support the bottom, and bars attached to the external surface of the two other opposite side walls, and projecting downward beyond the upper surface of said bottom and terminating approximately at the level of the under-side of said bottom in order to locate said bottom and said side walls in fixed interrelation, said abutments being disposed on said downwardly projecting bars.

2. A case as claimed in claim 1 in which said bars project upward beyond the under-side of said cover, and, at most, as far as the level of the upper surface of said cover.

3. A dismountable case comprising, in combination, a removable cover and bottom and four individually removable side walls which are vertical when the case rests on its bottom, and which are arranged in pairs oppositely and in parallel relationship to each other, vertical edge bars mounted at the adjacent edges of one of the pairs of opposite walls, means connecting said vertical edge bars to said other of the pair of side walls for preventing said one pair of side walls from falling outwardly, and abutment means mounted on the outer surfaces of the other of the pairs of opposite side walls and having portions located adjacent to said outer surfaces so as to provide a space between said portions and outer surfaces, said vertical edge bars mounted on said one pair of opposite side walls being located in said space, whereby the engagement of said vertical edge bars with said outer surfaces of said other pair of side walls prevents outward falling of said other pair of side walls and whereby engagement of said portions of said abutment means with said vertical edge bars prevents inward falling of said other pair of side walls.

4. In a dismountable case the combination of a removable cover and bottom and four individually removable side walls which are vertical when the case rests on its bottom, and which are arranged in pairs oppositely and in parallel relationship to each other, ribs being provided at two opposite vertical edges at the outer surface of each of two of the oppositely disposed side walls of said case, said ribs being disposed perpendicularly to said bottom, vertical edge bars at the adjacent edges of the other two opposite side walls, a longitudinal channel in each of said edge bars and opening toward the said ribs at the adjacent side walls, said ribs engaging said channels to prevent the first-mentioned rib-carrying side walls from falling outward, and abutment means mounted on said rib-carrying side walls and having portions located adjacent to the outer surfaces of said rib-carrying side walls so as to provide a space between said portions of said abutment means and said outer surfaces of said rib-carrying side walls, said channelled edge bars being located in said space, whereby engagement of said portions of said abutment means with said channelled edge bars prevents said rib-carrying side walls from falling inwardly.
